UNITED STATES PATENT OFFICE.

JOHN F. WALTON, OF BASTROP, TEXAS.

TOOL.

1,199,948.

Specification of Letters Patent.

Patented Oct. 3, 1916.

Application filed December 11, 1915. Serial No. 66,274.

To all whom it may concern:

Be it known that I, JOHN F. WALTON, a citizen of the United States, residing at Bastrop, in the county of Bastrop and State of Texas, have invented certain new and useful Improvements in Tools, of which the following is a specification.

My present invention relates to improvements in tools, one object of the invention being the provision of a claw hammer, which is provided with means for gripping the body of a nail at various points between the head and the body pierced, so that by a series of successive movements of the handle of the hammer with the hammer head as a fulcrum, the nail may be pulled.

A further object of the invention is the provision of a hammer head, having formed therein a nail pulling device, which renders it unnecessary to block the hammer when pulling an extra long nail, or wherein the nail must be bent in pulling, if the claw portion is only used.

A still further object of the present invention is the provision of a simple, durable and inexpensive attachment to a hammer, that permits longer nails to be pulled by a straight line movement and without bending the nail, and yet also provides a wrench by means of which bolts, small rods and also pipe may be turned, the handle of the hammer being used as the lever.

In the accompanying drawings:—Figure 1 is a side elevation of the present hammer with the attachment applied. Fig. 2 is a cross section on line 2—2 of Fig. 1. Fig. 3 is a sectional view taken longitudinally of the hammer, or at right angles to that shown in Fig. 2, the parts being in the position they assume before the introduction of a nail. Fig. 4 is a similar view showing a nail being pulled. Fig. 5 is a bottom plan view of the hammer. Fig. 6 is a perspective view of the detent or gripping member *per se*.

Referring to the drawings, 10 designates the handle, and 11 the hammer head. The head is provided with the usual claws 12, and intermediate of the inner end of the slot 13 of the claws and the opening 14 of the handle, is a small bore or opening 15, through which the head of a nail may be inserted to assume the position as shown in Fig. 4.

The irregular cross opening 16 is formed through the body of the hammer at a point adjacent to the inner end of the bore 15, the oppositely disposed faces being provided with teeth 17 and 18, while that surface having the teeth 18 is provided with a longitudinal slot 19, having the guide ribs 20, for the sliding reception of the detent or gripping member 21, which is carried by the rod 22. This rod is slidable in the bore 23 at the top of the slot 19, while a spring 24 embraces the same, and normally holds the detent toward the bore 15, with its toothed gripping face 25 projected to engage the nail N, as illustrated in Fig. 4. When the nail is first inserted within the bore 15, the detent is moved thereby and after the head of the nail passes the detent the spring snaps and pushes the same into the position as shown. The lower end of the slot 19, after the detent has been inserted therein is burred to prevent the detent from slipping entirely out of the slot.

Reinforcing braces 26 are formed integral with the hammer head, when found necessary.

The roughened faces of the opening 16 permit the introduction of a bolt, rod or pipe from the side of the head, so that the same may be turned by manipulating the handle of the hammer.

What I claim, as new, is:—

1. In a nail puller, the head of which is provided with a nail receiving bore and with a cross opening at one end of the bore, two of the walls of the cross opening being roughened, and a spring projected detent mounted in one wall of the cross opening and having a gripping portion for engagement with a nail when disposed within the bore.

2. In a nail puller, the head of which is provided with a nail receiving bore and a cross wise opening at one end of the bore, said opening being provided with one inclined flat wall having a longitudinal channel the lower end of which communicates with the bore, and a spring projected detent mounted in the channel and having a nail engaging face for disposition within the bore to engage a nail.

In testimony whereof I affix my signature,

JOHN F. WALTON.
